UNITED STATES PATENT OFFICE

HOWARD S. CRAVER, OF CHICAGO, ILLINOIS, ASSIGNOR OF ONE-HALF TO HENRY S. JUDD, OF CHICAGO, ILLINOIS.

WASHING MACHINE.

Application filed October 17, 1922. Serial No. 595,080.

To all whom it may concern:

Be it known that I, HOWARD S. CRAVER, a citizen of the United States, residing at Chicago, in the county of Cook and State 5 of Illinois, have invented a certain new and useful Improvement in Washing Machines, of which the following is a specification.

My invention relates to washing machines, especially of the type in which there 10 are clothes engaging elements which have a vertical reciprocating movement and also a step by step angular or rotary movement. Examples of such machines may be found in my prior Patents No. 1,361,228 and 15 1,412,924, and my co-pending application Serial No. 591,234 filed September 29th, 1922. In said co-pending application I have shown a machine in which there is a friction clutch for imparting a step by 20 step rotary movement to the clothes engaging elements; one advantage being that when said clothes engaging elements (which for convenience will be termed "cups") meet an obstruction they will stop their rotary 25 movements until the obstruction is removed. For one thing this avoids danger of wrapping the clothes around the center post and tearing them. In the machine there illustrated the clutch is thrown into and out of 30 engagement automatically by the action and reaction of the contents of the clothes receptacle on the cups. The present machine has the same general characteristics but shows a clutch and driving mechanism of 35 different construction. The object of my present invention is to provide an advantageous alternative design of clutch mechanism and associated parts.

In the accompanying drawings which 40 form a part of this specification,

Figure 1 is a side elevation of the machine showing the clothes receptacle in section.

Figure 2 is a side elevation of the clutch and associated mechanism, the clutch members and some of the other parts being 45 shown in diametral section.

Figure 3 is a plan view of the parts shown in Figure 2, certain portions of some of the elements being broken away to better reveal 50 the construction. The irregular line 3-3 Figure 2 indicates the points at which the parts are broken away.

Figure 4 is a side elevation of the clutch looking toward the left in Figure 2. Por-

tions of the clutch elements are shown in 55 section.

Figure 5 is similar to Figure 4 but shows the parts in changed position.

Like numerals denote like parts throughout the several views.

In the illustrated design the machine has a clothes receptacle 1 provided with a center post 2 rising from the bottom and forming a guide for a vertically reciprocating shaft 3. At the upper end of the shaft, 65 above the top of post 2, is a cross arm 3 which at its ends carries a plurality of clothes engaging elements 4, shown in the form of vacuum cups. The machine is driven by a motor 5 or other suitable source 70 of power which is here shown to be connected by a belt 6 to a sheave 7 geared to an eccentric 8 which actuates a link 9 connected at its lower end to a lever 10. Said lever has a fulcrum 11 which bears 75 in a horizontal slotted bracket 12, and said lever and associated parts compose the power mechanism. These parts or their analogues are shown in the earlier patents 80 and in the said pending application, and are not new in themselves.

Pinned or otherwise rigidly secured to shaft 3 near the lower end thereof is a clutch member 14 which faces downward and has a depending peripheral flange 16. A friction washer or gasket 18 encircles the shaft beneath disc 14 and rests upon a friction disc 20, which faces upward. The two discs 85 form 2 cooperating clutch members and the gasket 18 forms a clutch lining and may 90 consist of any of the well known compositions used for the purpose. It may be entirely omitted if desired.

Disc 20 is loosely mounted on shaft 3 and has two downward extending fingers 22, 95 which receive between them a pin 24 fastened to an eccentric 26 formed on one of the forks or branches at the outer bifurcated end of lever 10. Eccentric 26 is shown to have three apertures 27, either one of them 100 for receiving pin 24. By placing the pin in different apertures, different degrees of eccentricity may be obtained. Lever 10 is articulately secured by pins or trunnions 28 to a sleeve 30, which is loosely mounted on shaft 3. Said shaft is shouldered at its lower end and screw threaded to take a nut 32. It is desirable to interpose a washer 34

between the nut and the sleeve to reduce friction.

Operation: When eccentric 8 is rotated it will cause the lever 10 to swing up and down about its pivot 11. This causes sleeve 30 to move up and down, which vertical motion is transmitted to shaft 3 for the reason that when the sleeve is moving downward it will press down upon the washer 34 and nut 32, and when moving upward will engage the hub of the disc 20 and press it and clutch lining 18 upward against the clutch disc 14, which is fastened to the shaft.

Now as to the means for producing angular or rotary movement of the shaft: The parts are so proportioned that there is a slight amount of lost motion, vertically, of the parts located between the disc 14 and washer 34; consequently when the lever 10 and sleeve 30 move downward, the lower clutch member 20 will move slightly away from the upper fixed clutch member 14—or at least the pressure will be so reduced, due to the resistance which the cups 4 meet in moving downward against the clothes and water, that the clutch will be released and the lower clutch member will move angularly without transmitting any angular movement to the upper clutch member 14 (which is fastened to the shaft). As the pin 24 is eccentrically mounted on lever 10, that is, is located at a distance from the trunnions 28, the downward movement of the lever from the position shown in Figure 5 will swing pin 24 forward to the right, thus imparting a corresponding angular movement to the fingers 22 and lower clutch member 20 (toward the right Figure 5), but as the clutch members are out of engagement on this downward movement there will be no angular movement imparted to the shaft while it is descending. On the upstroke the lever 10 moves sleeve 30 upward toward disc 14, thus forcing the shaft upward and at the same time causing the lower clutch member to have frictional engagement with the upper clutch member. This condition is illustrated in Figures 2 and 4 where it will be noted that there is a slight space between washer 34 and the lower end of sleeve 30. This space is shown largely for the purpose of illustrating the principle of operation for it will be understood that in practice only a slight amount of lost motion is necessary, and in fact the motion may at times be so small as to be hardly perceptible. As the lever 10 moves upward from the position shown in Figure 4 it will not only move shaft 3 upward and move the loose disc 20 upward into frictional engagement with upper clutch member but will also cause pin 24 to move toward the left from the position shown in Figure 4. This causes a corresponding angular movement of the fingers 22 and disc 20. As the two disc members of the friction clutch are now in engagement this angular movement of the lower clutch member will impart a similar angular movement to the upper clutch member and to shaft 3, and to the cups 4 which are carried by it. Thus it will be evident that the clutch is thrown in and out automatically due to the vertical reciprocation of lever 10 and sleeve 30 and the reactive effect or drag of the contents of the clothes receptacle. In moving downward the cups 4 meet the resistance of the clothes and the water, and hence the lever 10 has to pull shaft 3 downward, thus causing a limited separation between the two clutch members. On the upstroke the clutch members are held in engagement not only by the weight of the shaft and parts carried thereby and by the inertia of the supported parts but also by the resistance of the water through which the cups must rise in moving to their uppermost position shown in dotted lines in Figure 1. Thus on the upstroke my mechanism automatically produces a rotary movement of the cups, but on the downward movement produces no rotative effect.

It will be evident that different degrees of tractive effect may be obtained between the two clutch members by varying the area thereof, and the condition of their cooperating surfaces and of the character of the clutch lining 18. For example, the amount of tractive effect may be increased by increasing the contacting areas and increasing their roughness. In actual practice this factor is so regulated that the cups will move angularly providing the resistance of the clothes is not excessive as would be the case, for example, if the clothes were wrapped around the center post 2. If by any chance the clothes should thus become wrapped around the center post the cups will simply continue their vertical movement without rotating and this action soon frees the clothes and permits the rotary movement to be resumed. Thus it will be evident that my machine eliminates all danger of tearing the clothes and also possesses the advantage that the operator if he wishes may hold the cups against angular movement without otherwise stopping the machine. This makes it possible to inspect the contents or remove a portion thereof without stopping the motor.

Having thus described my invention what I claim as new and desire to secure by Letters Patent is:

1. A washing machine having a clothes receptacle, a shaft which is vertical and angularly movable and provided with clothes engaging elements, a clutch including two friction elements, the upper one being fastened to the shaft and the lower one loosely mounted on it, and a power device for oscillating the lower friction element and simultaneously reciprocating it vertically.

2. In a washing machine, a reciprocating vertical operating shaft, clothes engaging elements carried by said shaft and compelled at all times to move angularly with it, a power device for moving said shaft vertically and a friction clutch including two discs, the upper disc being rigidly secured to the shaft and the lower disc loosely mounted thereon and adapted to support the upper disc, the lower disc being loosely supported by the power device and having a supplemental connection to it to be positively moved angularly by it.

5 by said shaft, a driving lever swinging in a vertical plane, a clutch having a tight and a loose member mounted on said shaft, the loose member mounted on said shaft, the loose member being below and adapted to support the tight member, a loose sleeve on the shaft below the loose clutch member and adapted to support it, the sleeve being connected to the lever to be reciprocated vertically by it, and an eccentric connection between the lever and the loose clutch member for oscillating the latter.

10

15

3. A washing machine having a clothes receptacle, a vertically reciprocating, rotatable shaft, clothes engaging elements carried

In witness whereof, I have hereunto subscribed my name.

HOWARD S. CRAVER.
